PARTICLE COUNTING APPARATUS

Hugh Alexander Dell, Horley, England, assignor, by mesne assignments, to North American Philips Company, Inc., New York, N. Y., a corporation of Delaware

Application March 23, 1954, Serial No. 418,050

Claims priority, application Great Britain March 23, 1953

8 Claims. (Cl. 250—217)

The invention relates to apparatus for counting particles and is particularly but not exclusively concerned with the assessment of the dust content of an air sample.

There has been disclosed in the copending application Serial No. 295,586, filed June 25, 1952, apparatus for effecting such an assessment which includes means such as a flying spot scanner of the cathode ray tube type for scanning the sample, the guard spot technique being employed to distinguish between a terminal interception of the particle by the main beam i. e. a first or last interception of the particle by the main scanning beam and other interceptions of the particle by both main and guard beams or by the guard beam alone, the normal scanning motions of the scanning beam being arrested when a particle is first (or last) "seen," the scanning beam being then caused to explore the particle to determine its nature or size after which the scanning beam resumes its normal scanning motions. The individual particle sizes are deduced from the information obtained by the explorations and the total number of particles from the number of times the normal scanning is arrested.

Whilst such an apparatus enables memory devices to be dispensed with, the use of the guard spot technique may have disadvantages in certain cases. On the other hand, the "arrested spot technique" above referred to enables, when desired, much more information to be obtained of the nature or size of the particles of a sample than from the more interaction of the scanning raster with the particles since at the most, in this latter case, only the length of the line intercepts of a particle or the number of complete scanning lines it overlaps can be obtained. With certain shapes of particles even this information may not be conveniently presented.

The object of the present invention is to provide a particle counting apparatus having the desirable attributes of the arrested spot scanning technique without the disadvantages of the "guard spot technique" for distinguishing between first (or last) and other interceptions of a particle.

According to the present invention a particle counting apparatus comprises particle sample scanning means including means for producing a scanning beam tracing out a rectilinear raster, scanning beam arresting means for arresting the normal scanning motions of the beam only when a terminal interception of the particle by the beam occurs, i. e. only when a particle is first (or last) intercepted, particle exploring means for causing the or a scanning beam (or beams) to explore a particle thus intercepted, line to line memory means for distinguishing between the first (or last) interception of the particle by the scanning beam and any other interceptions of the same particle and counting and sizing means giving a count of the total number of particles scanned and/or individual counts of particles of different natures or sizes.

According to a further feature of the invention the line to line memory means is of the cyclic type and comprises for example, a magnetic recording disc or drum

2

having a first channel bearing a single permanent recorded signal which, through the medium of a line synchronising reading head, is used to trigger or synchronise the line scan of the scanning means, a second recording channel on which an "explore" synchronising head writes a signal each time a particle is first (or last) intercepted and a third channel with which co-operate spaced writing and reading heads which respectively record the interception of particles in one scanning line and reproduce them during the succeeding scanning line. Signal erasing means are associated with the second and third channels for erasing, when required, the signals on these channels and switching means is also provided for energising or de-energising the reading and writing heads at appropriate times.

The memory means therefore performs three functions; first, it ensures that the commencement of each line scan takes place with the recording medium (disc drum or the like) in a pre-determined (angular) position, second, it stores signals (hereinafter called "particle signals") corresponding to all interceptions of particles in a scanning line and erases, if present, all previous particle signals and third, when, during the scanning of a line, a new particle is encountered, a signal (hereinafter called the "explore sync" signal) is written on the second channel and substantially simultaneously with the termination of this signal the aforesaid reading, writing and erase heads are de-energised, normal scanning of the sample is interrupted and exploration of the particle takes place. Resumption of normal scanning only takes place after a signal denoting the end of the exploration has appeared and when the emission of an explore sync signal from the explore sync head acting as a re-producer next takes place. By this means it is ensured that the recording medium is in the same (angular) position at the resumption of normal scanning as it was when the scanning was interrupted so that the particle signals in the third channel are recorded on the medium in the same spatial relationship as the particles in that particular scanning line. Thus, however, many new particles are discovered in a scanning line and in spite of possible and probable differences in exploration time for these particles, the recording means preserves an accurate record of the presence and distribution of all particles in that line until it has been used during the succeeding scanning line to distinguish between new interceptions and repeated interceptions of large particles extending from the preceding line. In this way, a modified form of the guard spot technique is carried out without the disadvantages associated with other practical embodiments of this technique.

Other features of the invention will be apparent from the following description of a practical embodiment which is given by way of example only with reference to the drawings in which:

Figure 1 is a schematic diagram partly in block schematic form of a dust particle counter according to the invention;

Figure 2 is a view of a position of a particle sample;

Figure 3 is a circuit diagram of a pulse limiter and shaper unit;

Figure 4 is a circuit diagram of a new signal indicator;

Figure 5 shows signal waveforms;

Figure 6 is a circuit diagram of a switch control unit;

and

Figure 7 is a circuit of a pulse producer.

In Figure 1, the scanning means is represented as a flying spot scanner incorporating a cathode ray tube 1, having deflecting means 2, to cause the cathode ray beam, when the tube is in operation, to trace out a rectilinear raster on the tube face. An optical system shown as lens 3 may be employed to focus an image of the flying

spot to the same or a different scale on the sample 4, and a further optical system, shown as lens 5, may be employed to cause the light passing through the sample to fall on a photo-electric pick-up device 6. It is assumed that the sample is a transparent plate on which dust particles or the like have been deposited and fixed or is a photographic reproduction of such a plate to the same or a different scale in either the positive or negative condition. Alternatively, the reproduction may be on an opaque surface in which case the pick-up device is suitably positioned so as to receive light reflected therefrom.

The output from the pick-up device is fed to a pulse limiter and shaper unit 7, which may be of the form shown in Figure 3, and which will be hereinafter more fully described.

The arrangement and functions of the remaining switching, control and recording units will be more clearly understood from the operation of the apparatus on a typical sample a portion of which is shown in Figure 2. The centres of three adjacent scanning lines are indicated at L₁, L₂ and L₃, line L₁ intersecting the four particles A, B, C and D, line L₂ intercepting particles B and C only and line L₃ intercepting particle C only.

The line scanning motion of the cathode ray beam is caused by the line time base 8 which is triggered by a pulse derived from a first channel of the magnetic memory unit 9 through the medium of the reproducing head 10 which will be known hereafter as the "line sync head." A frame scanning generator is denoted by 8'.

The memory unit 9 may be of the known disc or drum type having a magnetisable surface of sufficient extent to accommodate three separate recording channels and is rotated at substantially constant speed by a suitable motor. As a matter of convenience the drum may be arranged to make one half of a revolution for one complete uninterrupted line scan.

When the flying spot commences to scan line L₁ under the action of the line time base unit 8, no signal is emitted from the pick-up device 6 until particle A is encountered. Thereupon a signal is fed to the pulse limiter and shaper unit 7 which delivers a suitably shaped, for example, a substantially rectangular, pulse of the desired polarity to switches S₁ and S₂. Switch S₁ is normally in the position which passes the pulse to a writing head 11 associated with the third channel of the memory unit 9 to record thereon a particle signal representing particle A. Switch S₂ is, in the starting condition, in the position to pass the pulse to the "new signal indicator" 12 the function of which is to ascertain whether the received pulse represents a first or subsequent interception of a particle. This is achieved as will be more clearly described later by comparing the incoming pulse from the limiter 7 with any signal substantially simultaneously received from the reading head 13 associated with the third channel and disposed at for example 180° from the writing head 11.

In the case under review there is no signal from the reading head 13 since particle A is the first particle to be intercepted on the first scanning line so that the new signal indicator 12 passes a pulse to the switch control unit 14 and to the pulse producer unit 15. Upon the receipt of this pulse the switch control unit 14 functions to open switches S₁, S₅ and S₉ thereby isolating respectively the writing head 11, the reading head 13 and the erasing heads 16. It also opens switches S₂ and S₄ associated with the line and frame time bases which arrest the normal scanning motions. Further, it passes a signal to the signal routing switch 17 and to the explore switch 18. The routing switch 17 operates switch S₂ to the position in which any further signal from the pick-up 6 is routed to the explore switch 18 and the explore switch 18 operates the switch S₆ of the Y-direction shift unit 19 to energise this unit so as to cause the light spot produced by the cathode ray beam to explore the par-

ticle in the Y-direction. At the moment that the particle is encountered the pulse producer unit 15 passes a signal via switch S₆ to the explore sync write-read head 20 to cause it to record a signal on the second channel. The unit 15 also passes a signal to the sync switch 21 which operates to alter the position of switch S₈ so that any signals received from the head 20 acting as a reading head will be routed, as soon as exploration is completed, to both the switch control unit 14 and signal routing switch 17 via switch S₇ which was operated to its open position by explore switch 18 when this was initially energised.

Since particle A is a small one a small deflection of the exploring light spot will cause it to traverse the particle until it is "seen" by the pick-up device 6 which thereupon passes a signal to the explore switch 18 to cause it to be re-set thus terminating the exploration and operating switch S₇ to its closed position.

It will be appreciated that the time delay between the 20 interception of particle A and the end of its exploration depends on the size of the particle and during this period the magnetic memory drum will have rotated through an indeterminate angle which may be less or greater than one revolution. All that is necessary is that normal scanning should commence when the drum is in the same angular position as it was when particle A was first intercepted and this is ensured by the explore sync signal laid down in the second channel. When the drum reaches this position the explore sync head 20 acting as a reproducing head delivers a pulse through switch S₇ to the switch control unit 14 and to the signal routing switch 17. The unit 14 is thereupon re-set which causes closure of switches S₁, S₅ and S₉ and opening of switches S₃ and S₄ thus permitting normal scanning to be resumed. 25 30 Routing switch 17 is also re-set which causes switch S₂ to be operated to pass any new signal from the limiter 7 to the new signal indicator 12. Further, the pulse from the explore sync head 20 is passed to the sync switch 21 to re-set it thus operating switch S₈ to the position in 40 which the head can receive a new recording signal from the pulse producer 15 when the next particle is encountered. Since switch S₈ is closed the erase head 16 co-operating with the second channel erases the second channel explore sync signal thus clearing this channel 45 for subsequent use. The erase signal is provided by an erase signal source 24.

The units 12, 14, 15, 17, 18 and 21 and the switches 50 operated by them are thus once more in their starting condition and the first channel of the memory unit carries a record of the particle A at a position along the channel from its commencement corresponding to the position of the particle A in the first scanning line.

The complete sequence of operations above described is repeated when particles B, C and D are first encountered in line L₁, so that at the completion of this first line the third channel of the memory unit carries a record of these 55 60 65 70 75 80 85 90 95 100 105 110 115 120 125 130 135 140 145 150 155 160 165 170 175 180 185 190 195 200 205 210 215 220 225 230 235 240 245 250 255 260 265 270 9420 9425 943

At this moment the new signal indicator 12 receives a signal from the limiter 7, being the second interception of particle B and, approximately simultaneously, a signal from the head 13 representing the first interception of the particle. When such signals are received by the new signal indicator 12 it does not operate, so that normal scanning proceeds, in this case to the end of line L₂, without further interceptions since particle D does not extend into line L₂.

During the scanning of line L₂ the memory unit has revolved through one half a revolution and at the completion of the scan of line L₂ the third channel record of line L₁ has been erased by the erase head 16 which operates with this channel as well as the second channel.

At the completion of the scan line L₂ the third channel of the memory unit carries signals representing the second interceptions of particle B and C for comparison with such signals as may be received in line L₃.

In the example shown only particle C overlaps line L₃ so that scanning of this line will proceed from end to end without the flying spot being arrested and at the end of the line the signals in the third channel of the memory unit, representing the interceptions in line L₂, will have been erased and only the interception of particle C in line L₃ will remain for use during the succeeding scanning line.

It will be clear from the above description that each time the flying spot is arrested to explore a particle the Y-direction shift unit is operated and the measured size of the particle being explored will be for example, a function of the time the unit is in operation or proportional to a potential which varies with Y-direction deflection. The latter case is diagrammatically illustrated by the resistor 22 across which a potential appears when a capacitor whose charge is related to the extent of the exploration scan, is discharged at the termination of the exploration. At the termination of the exploration the switch S₆ is returned to the position in which the Y-direction shift unit is de-energised or blocked (the lower position in Figure 1) and the transient potential generated across the resistor 22 is passed to a pulse height analyser and counter 23 of known form. Thus, as scanning of the sample proceeds, a train of pulses having a random distribution in time and having varying amplitudes will be presented to the analyser 23 which may present an analysis of the pulse train in any convenient manner for example the pulses may be sorted into any arbitrary number of groups so that individual counts of particles in each group may be presented as well as a total count of all the particles. This latter count, may, if desired, be simply derived from the number of times the switch control unit 14 is operated.

Suitable circuit arrangements given by way of example only for the limiter unit 7, the various switch units and the pulse producer 15 will now be described with reference to Figures 3, 4, 5, 6 and 7.

The limiter unit

One suitable circuit for the limiter unit is shown in Figure 3 and may comprise a cathode coupled double triode thermionic valve 24a, 24b. The signals from the pick-up device 6 are impressed on the control grid of the triode 24a and the anode is connected through resistor 25 to the control grid of triode 24b, this grid being connected through resistor 26 to a negative potential source. The anodes of the triodes are connected to a positive H. T. line through load resistors 27, 28 respectively and the circuit values are so adjusted that pulses over a predetermined amplitude result in the production of substantially rectangular and constant amplitude pulses at the anode of triode 24b.

If it is assumed that the potential of the output of the pick-up device rises as the scanning beam encounters a particle and drops as it leaves the particle then the limiter 7 will deliver a positive going pulse of substan-

tially rectangular form and having a length representative of the length of the particle in the direction of line scan.

New signal indicator

The positive going pulses from the limiter 7 are, as above described, passed to the new signal indicator 12 which also receives signals from the read head 13 associated with the third channel of the memory means. The new signal indicator 12 may be of the form shown in the circuit diagram of Figure 4. In this circuit the signal from the limiter 7 is, after differentiation in the normal manner, applied to the anode of diode V₁ the cathode of which is connected to the control grid of triode valve V₂ which acts as a pulse inverter. Signals appearing at the anode of valve V₂ are applied to the control grid of valve V₃ which with valve V₄ forms a bi-stable multivibrator, the anode of valve V₃ being connected to the control grid of valve V₄ and the anode of valve V₄ being connected to the control grid of valve V₃ in the usual manner. The differentiated incoming signal is also applied to the suppressor grid of the valve V₄ and the control grid of this valve is connected to a negative H. T. line through a resistor 29 across which is shunted triode valve V₅. The anode of valve V₅ is therefore coupled to the control grid of valve V₄ and has its cathode connected to the negative H. T. line. The particle signal, produced by the read head, which will be assumed to be a positive-going signal of substantially rectangular waveform, is applied to the control grid of valve V₅.

The method of operation of this circuit is as follows: Initially the valve V₃ is conducting and the valve V₄ is cut off on its control grid and valve V₅ is non-conducting due to the connection of its control grid to a negative bias line designated -HT² in Figure 4.

Considering first the operation at the first interception of a particle, the positive-going pulse produced by the differentiator representing the leading edge of the particle traverses valve V₁ and causes valve V₂ to conduct so that a negative pulse from the anode of this valve is passed to the control grid of valve V₃. Valve V₃ is thereby cut-off and the multivibrator flips to its other stable state in which valve V₄ is conducting being open both on its control grid and its suppressor grid.

When the negative pulse produced by the differentiator representing the trailing edge of the particle appears it cannot effect the control grid of valve V₂ due to rectifier valve V₁ but it appears on the suppressor grid of valve V₄ limiting the current to the anode, which causes the multivibrator to flop to its initial stable state. Substantially the whole of the emission current of the valve momentarily goes to the screen grid, the potential of which exhibits a negative pulse which is passed to the switch control unit 14 and the pulse producer 15.

Considering now the operation of the indicator, for example under the condition of the second interception of particle B (line L₂) and assuming that the signal from the read head 13 appears slightly before the signal from the limiter 7 then the control grid of valve V₅ will go positive so that V₅ fully conducts and reduces the potential of the control grid of V₄. When the positive pulse of the differentiated signal from the limiter 7 is applied the valve V₂ and the corresponding negative-going pulse is applied to valve V₃ the multivibrator cannot flop since the control grid of valve V₄ is being forceably held at a very low potential. Thus, when the negative-going pulse of the differentiated signal is applied to the suppressor grid of valve V₄ no signal appears on the screen grid and there is no output to the switch control unit 14 or pulse producer 15.

In Figure 5 are shown (in pairs) the waveforms of the signals produced by the limiter 7 (after differentiation) and the read head 13 for various types of particles. The waveforms shown at (a) represent the first interception of a particle and at (b), (c), (d) and (e) interceptions after the first for various shapes of particle

overlapping two or more scanning lines. The waveforms at (b) are produced when a long substantially parallel sided particle sloping in the direction of line scan, is encountered and at (c) when such a particle slopes in the opposite direction at (d) and (e) are shown the waveforms produced when a particle having tapering sides is encountered in the case of (d) the sides are divergent in the direction of frame scan and in (e) convergent in the same direction. At (f) the read head signal alone is present (for example when the memory unit provides in line L₂ a signal corresponding to the first interception of particle A in line L₁).

In each of these cases (b) to (f) no signal is passed on to the switch control unit 14 since the read head signal has either prevented the multivibrator being set or has returned it to the condition in which it is non-responsive to the trailing negative-going pulse of the differentiated signal from the limiter 7.

Switch control unit

As above described the new signal indicator only emits a pulse when a particle is first intercepted and this pulse is passed to the switch control unit 14 now to be described and to the pulse producer 15 which will be later described. A suitable circuit for the switch control unit is shown in Figure 6. This unit may conveniently comprise a cathode coupled double triode thermionic valve V₆, V₇ forming a bi-stable multi-vibrator. The anode of valve V₆ is connected to the control grid of valve V₇ and the anode of valve V₇ is cross-connected to the control grid of valve V₆. Both control grids are connected through grid leaks to a negative H. T. line and the anodes are each connected to a positive H. T. line through load resistors. Negative-going signals from the new signal indicator 12 are applied to the control grid of valve V₆ which is initially in the conducting state the valve V₇ being cut off. The multivibrator may be tripped to its original stable condition by negative going signals applied to the control grid of valve V₇ these signals being those derived from the explore sync head 20.

Upon the application of a negative pulse from the new signal indicator 12 a negative-going pulse appears at the anode of valve V₇ and this may be utilised to open switches S₁, S₃, S₄ and S₅.

Since these switches have been shown diagrammatically as mechanical switches there is included in the anode circuit of valve V₇ a multi-contact relay 30 of which the contacts constitute the aforesaid switches. It will be clear, however, that such mechanical switches may be replaced by electronic switches in which case of course the relay is not employed.

The negative going pulse appearing at the anode of valve V₇ when an input signal is received from the new signal indicator 12 is, as above stated, passed to the signal routing switch 17 to cause it to actuate switch S₂ to the position in which signals from the limiter 7 are passed to the explore switch 18 which in turn operates switch S₆ and opens switch S₇.

Both the signal routing switch and the explore switch may be of exactly the same type as the switch control unit above described so that further description of these items is not necessary. The sync switch 21 the position of which has to be set by a pulse from the pulse producer 15 and re-set by a signal from the explore sync head 20 can also employ the same circuit as that shown in Figure 6.

Pulse producer

A suitable circuit for the pulse producer is shown in Figure 7. This may conveniently comprise a cathode coupled double triode thermionic valve V₈, V₉ having the anode of valve V₈ connected to the control grid of valve V₉ through a capacitor C the control grid being

connected to the earth line through a resistance R the time constant of CR being suitably proportioned. Negative-going input pulses from the new signal indicator 12 are applied to the control grid of valve V₈ which may be suitably biased. In the initial or starting condition valve V₈ is conducting and valve V₉ is cut off. Upon the receipt of a negative going pulse at the control grid of valve V₈ this valve ceases to conduct and valve V₉ becomes conducting so that the potential at the anode of valve V₉ drops. After a time delay, determined by the time constant of CR, the valves V₈, V₉ which form a mono-stable multi-vibrator revert to their initial condition so that a substantially rectangular pulse, having the desired duration in time, is available at the anode of valve V₉. This pulse is fed to the explore sync head 20 whenever a particle is first intercepted so as to record a signal in the second channel which is available, as above described, for synchronising the action of the scanning means with the rotation of the memory drum.

It will be understood that the invention is not limited to the arrangements described with reference to the block schematic diagram of Figure 1 since the magnetic memory device may be replaced by any other suitable device performing the same functions. Further, the invention is not limited to the simple exploration of the particles as described herein. Such exploration may be of any other convenient or desired form. Such other methods of exploration may involve the use of more than one scanning flying spot. Such arrangements may involve alternation of the pick-up means 6 since more than one such means may be necessary but such changes will be obvious to those skilled in the art.

It will be understood that the invention is not limited to the particular circuit arrangements herein described since changes may be made to suit particular circumstances as they arise in practice.

What is claimed is:

1. Particle counting apparatus comprising particle sample scanning means including means for producing a scanning beam tracing out a rectilinear raster, scanning beam arresting means for arresting the normal scanning motions of the beam only when a terminal interception of a particle by the beam occurs, particle exploring means for causing the scanning beam to explore a particle thus intercepted, line to line memory means for distinguishing between the said terminal interception of the particle by the scanning beam and any other interceptions of the same particle and counting and sizing means giving a count of the number of particles scanned and distinguishing between particles of different sizes.
2. Particle counting apparatus as claimed in claim 1 wherein the line to line memory means is of the cyclic type having a plurality of independent signal channels the first of which carries a permanent signal which is utilised to trigger the line scan of the scanning beams.
3. Particle counting apparatus as claimed in claim 2 wherein the second of said signal channels carries particle signals corresponding to all interceptions by the scanning beam of particles in a scanning line.
4. Particle counting apparatus as claimed in claim 3 including means for writing said particle signals in said second channel during scanning of a line and means for reading said signals during scanning of the succeeding line.
5. Particle counting apparatus as claimed in claim 2 wherein a third of said signal channels is adapted to store an explore sync signal each time a new particle is encountered by the scanning beam.
6. Particle counting apparatus as claimed in claim 5 including means functioning as both writing and reading means for writing and reading said explore sync signal in said third channel and means for erasing said signal after it has been read.
7. Particle counting apparatus as claimed in claim 6 comprising means for de-energizing said scanning beam arresting means after exploration is completed and when

the associated explore sync signal is emitted by said reading means.

8. Particle counting apparatus as claimed in claim 2 wherein the line to line memory means comprises a magnetic recording element.
